UNITED STATES PATENT OFFICE

2,458,901

SCALP CONDITIONING CABINET

Clifford Fields, Mount Vernon, Ill.

Application December 18, 1946, Serial No. 717,039

5 Claims. (Cl. 128—375)

1

This invention relates to a device which is especially adapted for treating the human scalp to invigorate the growth of hair thereon.

Specifically, the invention deals with a hair and scalp-conditioning cabinet equipped with a steam generator and a ray-emitting lamp for treating the hair and scalp.

According to this invention a cabinet constructed of metal, wood, or any suitable structural material, is arranged with front, rear, side, and bottom walls together with an open top. A cover is provided for the open top. The front wall is apertured for receiving a human head. An oval-shaped aperture is preferred. A head rest, preferably padded or cushioned, is provided at the bottom of the aperture. A sliding door is mounted on the front face of the cabinet to overlie the upper portion of the aperture for resting on the forehead of a patient to adapt the aperture to a snug fit around the patient's head. The sliding door and the aperture-defining portion of the cabinet are each padded or cushioned to protect the patient's head and to provide a comfortable fitting arrangement for the head of the patient.

A rack, composed of spaced parallel rods, spans the interior of the cabinet at a level beneath the aperture. The rack is preferably inclined downwardly from the front to the rear wall of the cabinet. The rear wall is equipped with a receptacle for a lamp such as an infrared, ultra-violet, or the like ray-emitting device. The lamp is mounted at a level above the rack so that its rays will be concentrated on the scalp of a patient's head in the cabinet. The steam generator is mounted in the bottom of the cabinet beneath the rack and fills the entire cabinet with steam. In order to protect the patient's forehead against steam condensate droplets, a baffle is preferably mounted in the cabinet over the head of the patient.

A temperature regulator is provided for both the lamp and the steam generator to control the temperature of the interior of the cabinet.

A feature of the invention resides in the provision of a treating device for the entire scalp without subjecting the face of the patient to the treating zone.

A further feature of the invention resides in the provision of a scalp-conditioning cabinet which steams the entire scalp of the patient while the patient reclines in a comfortable position and is protected from the steam atmosphere except at the scalp area.

An object of the invention is to provide a

treating cabinet for the scalp and hair which simultaneously subjects the scalp and hair to the action of steam and light rays.

A further object of the invention is to provide a treating cabinet having an aperture for receiving a portion of a human body arranged to seal off the remaining portion of the body from the cabinet and equipped with means for creating a desired treating atmosphere in the cabinet.

A still further object of the invention is to provide a treating cabinet for a portion of a human body without subjecting any other portion of the body to the influence of the treating atmosphere.

A specific object of the invention is to provide a scalp and hair conditioner with a vapor-diffusing rack adapted to support the hair.

A further specific object of the invention is to provide a scalp-conditioner cabinet having a steam generator and a ray-emitting lamp controlled by a temperature regulator to maintain predetermined temperature conditions in the cabinet.

Other and further objects of the invention will be apparent to those skilled in the art from the following detailed description of the annexed sheet of drawings which, by way of a preferred example only, illustrates one embodiment of the invention.

On the drawings:

Figure 1 is a side elevational view, with parts broken away and shown in vertical cross section, of a scalp-conditioning cabinet according to this invention and illustrating the manner in which the cabinet is used to treat the scalp and hair of a patient.

Figure 2 is a front elevational view of the cabinet of Figure 1.

Figure 3 is a top plan view of the rack in the cabinet.

Figure 4 is a vertical cross-sectional view, with parts in elevation, taken along the line IV—IV of Figure 2.

Figure 5 is an enlarged fragmentary end elevational view taken along the line V—V of Figure 3.

Figure 6 is an enlarged fragmentary transverse cross-sectional view taken along the line VI—VI of Figure 2.

Figure 7 is a transverse horizontal cross-sectional view taken along the line VII—VII of Figure 2.

As shown on the drawings:

In Figure 1 the reference numeral 10 designates generally the scalp-conditioning cabinet of this invention arranged to receive the hair H and

scalp portion S of the head of a patient P reclining on a table T. The cabinet 10 is on rollers 11 and can be conveniently moved to a desired treating location, for example, adjacent a barber chair.

As best shown in Figures 1, 2, 4, and 7 the cabinet 10 has an open top, a front wall 10a, a rear wall 10b, side walls 10c, 10c, and a bottom 10d. The open top is closed by a cover 12 which, as shown in Figure 4, is hingedly connected to the upper end of the rear wall 10b by hinges such as 13.

An oval-shaped aperture 14 is provided in the front wall 10a at a level near the upper end of the cabinet. The aperture 14 has the major axis thereof extending vertically and is sized to accommodate a human head therein. A head rest 15 is secured to the front wall 10a and projects forwardly therefrom at the lower part of the aperture 14. This head rest 15 is provided with a concave portion 15a in the upper face thereof for fitting around the back of the patient's head. A soft pad, such as a rubber cushion 16, covers the head rest 15. A door 17 is slidably mounted on the front face of the front wall 10a in vertical channels provided by Z-strips 18, 18 secured to the front face of the front wall. As best shown in Figure 6, each strip 18 has a leg 18a secured to the wall 10a, a web 18b extending outwardly from the wall 10a, and an inturned leg or flange 18c overlying the door 17. A rubber gasket 19 is preferably interposed between the door 17 and the front wall 10a to sealingly engage the front wall. The gasket 19 is secured to the door 17 and prevents leakage of steam, as will be herein-after more fully described, between the door and cabinet wall. In addition, the gasket 19 is useful in holding the door 17 at a desired level, since the gasket material rubs on the cabinet wall. This rubbing action is sufficient to prevent the door from falling, and the weight of the door is therefore not borne on the forehead of the patient.

The door 17, as best shown in Figure 2, has a recessed bottom edge 17a extending around the upper portion of the aperture 14. This recessed portion 17a, as shown in Figure 1, is lined with a soft pad or rubber cover 20 to rest on the forehead of the patient. As therein shown, the back of the patient's head rests on the pad 16 of the headrest 15, while the scalp portion S of the head projects into the interior of the cabinet. The door 17 is lowered to close whatever portion of the aperture 14 that is exposed above the patient's head. The recess 17a of the door fits around the upper portion of the patient's head and seals off the aperture.

An inclined baffle 21, shown in Figures 1, 2, and 4, is mounted on the inner face of the front wall 10a at the top thereof and projects into the cabinet in spaced overlying relation to the patient's head. The baffle 21 has an upturned lip or flange 21a along the lower free end thereof to define a trough for directing condensate on the baffle to the side edges thereof which, as shown in Figure 2, extends well beyond the sides of the aperture 14. The baffle 21 extends inwardly into the cabinet beyond the scalp S of the patient, and any condensate collected thereon or dripping from the cover 12 will not fall on the patient's head, but will be drained to the end of the baffle beyond the patient's head.

The rear wall 10b of the cabinet, as shown in Figure 4, has an aperture 22 therein opposite the aperture 14 of the front wall. A casing 23 mount-

ed on the rear wall 10b provides a lamp chamber 24 communicating with the aperture 22 and receiving a ray-emitting lamp 25. The lamp, as illustrated in Figure 2, is arranged to direct its rays toward the aperture 14 for treating the scalp S of a patient's head projecting through the aperture. The casing 23 is used so that the overall dimensions of the cabinet 10 can be maintained at the minimum. Alternatively, of course, the lamp 25 could be directly mounted in a cabinet of larger dimensions.

A rack 26, shown in Figures 1, 3, and 4, spans the interior of the cabinet beneath the aperture 14. The rack 26 includes a rectangular metal frame band 27 removably resting on brackets 28 on the front and rear walls of the cabinet. The band 27 has spaced open-topped recesses 27a, best shown in Figure 5, along the side legs thereof and glass tubes 29 are removably mounted in these recesses. The tubes extend across the width of the cabinet between the side walls 10c, 10c and are in spaced parallel relation with the front and rear walls 10a and 10b. While glass tubes are preferred, it should be understood that any type of rod or tube could be used. The tubes are removable from the rack and the rack is removable from the cabinet.

The rack 26 is inclined, as shown in Figures 1 and 4, and slopes downwardly from the front wall beneath the head aperture to a lower level at the rear wall. As shown in Figure 1, the hair of the patient rests on the tubes of the rack, and can be spread loosely on these tubes.

In addition to providing a support for the hair of the patient, the tubes serve the dual function of deflecting steam and vapor as it rises through the rack, thereby causing it to contact every strand of hair and all areas of the scalp. The tubes are preferably about three-eighths of an inch in diameter and are placed about three-eighths of an inch apart.

The entire rack 26 can be easily removed out of the open top of the cabinet, or individual tubes can be removed through the open top of the cabinet out of the frame band 27.

A sloping false bottom 30 is mounted in the cabinet above the bottom 10d thereof. This false bottom 30 slopes to a drain valve 31 mounted on a side wall 10c. The drain valve can be opened at intervals to remove condensate from the cabinet.

A steam generator 32 is mounted on the false bottom 30 and includes an open-topped pan 33, a pair of electrodes 34 in the pan near the bottom thereof, a water supply tube 35 communicating with the interior of the pan 33 at the bottom thereof, and with an open-topped feed pan 36 on the outside of the cabinet on the side wall 10c. A water bottle 37 is mounted in inverted position on the outside of the cabinet in a retainer 38 and has its open mouth 37a in the pan 36 at a level to control the level of water in the pan 33 of the steam generator. Water is automatically fed from the bottle 37 to the pan 33 and maintained at a desired level in the pan. The electrodes heat the water in the pan 33 to generate steam, and the steam rises through the rack 26, being deflected by the tubes to circulate around the hair and scalp of the patient. The entire interior of the cabinet is flooded with steam.

As shown in Figure 4, the lamp 25 and steam generator 32 can be selectively or simultaneously operated, and the temperature of the interior of the cabinet can be maintained as desired by the setting of a thermostat switch 40. The switch

is mounted in the front wall 10a of the cabinet. To energize the lamp 25 and the electrodes 34, a socket plug 41 is mounted in the rear wall 10b of the cabinet beneath the false bottom 30. A wire 42 extends from one post of the plug 41 to the lamp 25 and a switch 43 on the rear wall of the cabinet 10b selectively controls current flow through this wire 42. A second wire 44 extends from the lamp 25 through the space between the bottom 10d and the false bottom 30 and to the switch 40. Another wire 45 extends from the switch to the other post of the plug 41. When the switches 40 and 43 are closed, the lamp 25 will be energized.

One electrode 34 of the steam generator is connected to a post of the plug 41 by a wire 46, and the other electrode of the steam generator is connected to the wire 44 through a wire 47 having a switch 48 controlling flow therethrough. When the switches 48 and 40 are closed, current will flow through the wires 46, 47, 44 and 45 to energize the electrodes, thereby heating water in the pan 33 and generating steam. The switches 43 and 48 selectively control the lamp and the steam generator and either one or both of these units can be energized from the plug 41. The thermostat switch 40 can be set from outside of the cabinet to de-energize the lamp and/or steam generator whenever temperature in the cabinet reaches the selected temperature. This arrangement gives automatic control for both heating units in the cabinet.

If desired, a heating lamp, such as an infrared ray lamp, can be replaced with an ultra-violet ray lamp, or other ray device.

From the above descriptions it will be understood that the invention provides a treating device especially adapted for invigorating the scalp of a human head. The device steams the entire scalp area and hair of a human head without subjecting other parts of the body to the treating atmosphere. At the same time, rays from a treating lamp are directed on the scalp. Medication can be applied to the scalp before treatment in the cabinet. The open top of the cabinet affords easy access to arrange the hair on the deflector, and to make proper adjustments.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A treating device comprising a cabinet having a head-receiving aperture, a rack spanning the cabinet interior below said aperture and adapted to support hair thereon, a steam generator in the cabinet beneath the rack to supply steam to the rack for flooding the cabinet, a ray-emitting lamp communicating with the cabinet above the rack to direct rays on the head of the patient, and a thermostat control device for the lamp and the steam generator to de-energize the same when the cabinet temperature reaches a preset degree.

2. A scalp-treating cabinet comprising an open-topped box having an apertured front wall intermediate the top and bottom thereof, a cover for the open top of the box, a door slidable on said wall of the box for partially covering said aperture to vary the effective size thereof, a rack

spanning the interior of the box beneath the aperture and inclined downwardly from the apertured wall, said rack having spaced hair-supporting members therein, a steam generator in the bottom of the box beneath said rack, and a ray-emitting lamp communicating with the box above said rack and arranged to direct rays toward the aperture in said wall of the box.

3. A scalp-conditioning cabinet comprising a cabinet having front, rear, side, and bottom walls together with an open top, a cover on said cabinet for selectively closing said open top thereof, said front wall of the cabinet having an oval-shaped opening therethrough intermediate the top and bottom thereof and sized for receiving a human head, a head rest on the front wall of the cabinet at the lower portion of said aperture, a door slidable on the front wall of the cabinet over the upper portion of said aperture, said head rest and said door being covered with soft material for respectively engaging the forehead and back portion of the head of a patient, an inclined baffle in said cabinet overlying the space occupied by the head of a patient in said cabinet, a rack composed of spaced rods spanning said cabinet at a level therein beneath said aperture, and a steam generator in the bottom of said cabinet.

4. A scalp-conditioning cabinet comprising an open-topped cabinet having an apertured front wall adapted to receive a human head therein, a head rest on said front wall surrounding the lower portion of the aperture, a door slidable on said front wall for partially covering the upper portion of said aperture, a baffle in said cabinet extending inwardly from said front wall above said aperture and projecting into the cabinet beyond the space occupied by the head of a patient projecting through said aperture, a plurality of spaced parallel rods spanning the cabinet at a level beneath said aperture, said rods extending in parallel relation with the front wall of the cabinet, and a steam generator in the cabinet beneath said rod.

5. A scalp-conditioning cabinet which comprises an open-topped cabinet having a head-receiving aperture in the front wall thereof, a frame band removably supported in said cabinet in inclined relation beneath the aperture in said front wall of the cabinet, said frame band having sides with open-topped recesses therein, glass tubes removably supported in said recesses and extending across the interior of the cabinet in spaced parallel relation with the front wall, and a steam generator in the bottom of the cabinet beneath said tubes arranged to circulate steam to flood the entire interior of the cabinet.
